UNITED STATES PATENT OFFICE,

THOMAS B. ATTERBURY, OF PITTSBURG, PENNSYLVANIA.

DESIGN FOR A MUSTARD-CUP.

SPECIFICATION forming part of Design No. 18,457, dated July 17, 1888.

Application filed May 26, 1888. Serial No. 275,248. Term of patent 7 years.

To all whom it may concern:

Be it known that I, THOMAS B. ATTERBURY, a citizen of the United States, residing at Pittsburgh, in the county of Allegheny and State of Pennsylvania, have invented and produced a new and original Design for Mustard-Cups; and I do declare the following to be a full, clear, and exact description of the same, reference being had to the accompanying drawing, forming a part thereof.

In the drawing I have shown the head and neck of a bovine in perspective, the head being detached from the neck portion.

The leading features of my design consist of a cup which forms a portion of the neck and the lower jaw and an upper portion forming the cover, representing the head of a bull or other animal of the bovine species, the cover and base forming a cup or receptacle for mustard.

A indicates the cup-receptacle or bottom of the mustard-cruet, and represents in general outline the neck and lower jaw of a bull.

B is the cover for the cup and represents the upper portion of a bull's head, with the 25 eyes, ears, nose, and horns.

C represents the curvature of the upper lip of the animal, forming an opening between the cover B and lower portion, A, through which the handle of the ladle projects, thus forming 30 the tongue D.

What I claim is—

The design for a mustard-cup, as herein shown and described, the same consisting of the receptacle A, cover B, and ladle D, the whole 35 composing upon its outer surface the conventional configuration of a bull's head and neck, as set forth.

In testimony whereof I affix my signature in presence of two witnesses.

THOS. B. ATTERBURY.

Witnesses:
